UNITED STATES PATENT OFFICE.

CHARLES E. WILCOX, OF ANAHEIM, CALIFORNIA, ASSIGNOR TO ELIHU C. WILSON.

WELL-PIPE ELEVATOR.

Original application filed January 29, 1921, Serial No. 440,933. Divided and this application filed May 28, 1923. Serial No. 342,143.

To all whom it may concern:

Be it known that I, CHARLES E. WILCOX, a citizen of the United States, and a resident of Anaheim, in the county of Orange 5 and State of California, have invented new and useful Improvements in Well-Pipe Elevators, of which the following is a full, clear, and exact disclosure.

This invention relates to well pipe elevators; and this application is divisional of 10 an application filed by me on January 29th, 1921, Serial No. 440,933, also entitled Well pipe elevator. In said prior application I have described a well pipe elevator wherein 15 the suspension bails or links are so associated with the pipe encircling body of the elevator as to cause the effectual lifting contact of the links with the body to be positioned comparatively closely under the load supported 20 by the elevator; and also so as to allow the links, although normally insured against accidental disengagement from the elevator body, to be easily removable from the body when so desired. This present application is 25 filed for the purpose of covering the second mentioned feature of the device shown in my said prior application, and the claims herein are directed to that feature while the claims in said prior application will be directed 30 to the first mentioned feature. Any claims to a combination embodying both features will also be included in said prior application.

It is a general object of the invention set 35 out in this present application to provide an elevator of simple and strong construction and in which the supporting bails or links may be easily removed from the elevator body, but are at the same time prevented 40 from becoming accidentally detached when the elevator is in use. I am aware that heretofore, for instance, in the patents of E. C. Wilson #1,314,996, well elevator, dated September 2, 1919 and #1,341,957, hoist, dated 45 June 1st, 1920, devices have been made known for making the supporting bail or link of an elevator removable from the pipe encircling structure or body. In comparison with such devices it is an object of 50 my invention to provide a simple arrangement, and particularly one that does not need the manipulation of a bolt or screw or the removal of any parts in order to attach or detach the bail.

The objects and features of the invention 55 will be best understood from the following detailed description of a preferred embodiment of the invention, reference for this purpose being had to the accompanying drawings in which:

Figure 1 is a plan section of the elevator taken as indicated by line 1—1 on Fig. 2;

Fig. 2 is a side elevation of the elevator;

Fig. 3 is an opposite side elevation of the body of the elevator; and

Fig. 4 is an end elevation of the elevator with its bails.

In the drawings I show a substantially circular casing encircling body or structure 10 that is preferably made up in two semi-circular halves 11 and 12 hinged together at one side at 13 and adapted to be releasably held together at their opposite sides by a latch device 14, the details of which it is unnecessary here to describe as I make 15 no claim to the latch in itself, it being the subject matter of U. S. Letters Patent No. 1,498,141, issued on June 17, 1924 to E. C. Wilson entitled Well elevator. Any sort of latch or lock may be used; in fact, so far as 20 this application is concerned, the details of structure and design of the casing encircling body in themselves are of no consequence.

Each semi-circular half 11 and 12 has a 25 laterally projecting lug 20 in the lower part of which there is a notch that has a comparatively restricted opening 21; that is, this notch has an inner part 22 that is somewhat greater in diameter or lateral dimension than the width of the opening 21. The actual effective width of opening 21 is 30 also preferably less than the diameter of the round bar from which the bails 23 are formed, so that the bails can only be passed through openings 21 by bringing their reduced parts, at the flats 24, into registration with openings 21. The inner part 22 of each notch is preferably of enough larger diameter than the bails to allow the bails 35 to play freely in 22, as will be apparent from the drawings. The lower ends of the bails are curved in the aspect seen in Fig. 4, and the walls of notches 22 are also curved, as indicated at 22' in Figs. 3 and 4. The 40 notches, as seen in the drawings, extend inwardly and upwardly into lugs 20 and into the body proper; so that it is also necessary

to move the bails down in order to disconnect them from the body. These notches also preferably extend inwardly to such a degree that they come close to or extend clear into the inner pipe receiving opening 30 of the elevator, and the bails are curved inwardly at their lower ends, in the aspect shown in Fig. 2, so as to reach into the inner parts of the notches and so that their lower ends, 5 where they engage the elevator body, are positioned as closely as possible under the load that is carried by the elevator. This last mentioned positioning of the notches and corresponding shape of the bails is, however, not claimed herein as it is the subject 10 matter of my said co-pending application.

Bails 23 may be formed in any suitable manner, they are usually formed as shown in the drawings with relatively long and 15 substantially straight side portions 31 in which the flats 24 are formed to make reduced portions. It will be understood that these reduced portions may be formed in any manner however, the flats are merely a convenient way of forming a reduced portion 20 in a bail of circular cross section.

The notch openings 21 in addition to being narrower than notch parts 22, and, preferably, narrower than the bail itself, are also 25 placed in a diagonal position, as most clearly shown in Fig. 4. (The actual width of openings 21 does not directly show in the drawings due to the fact that the opening is diagonal in both the aspects of Figs. 2 and 3. But the actual width of the opening is less than the diameter of the bail and slightly greater than the dimension "C" between flats 24.) As a result it will be seen 30 that the bails, in their normal or operating positions, cannot become disengaged from the body; because the openings 21 are narrower than the bail; and because the lower end part of the bail that is then in proximity to opening 21 is curved, in the aspect seen 35 in Fig. 4, while the notch opening is straight as seen in that aspect; and because the bail, where it passes through the notch, extends generally transversely while notch opening 21 extends diagonally. Furthermore, when 40 the elevator is suspended in normal operation particularly with the weight of the pipe on the body, the bails cannot move downwardly relative to the body to get to a point opposite the openings 21. But when the elevator is not in operation, then each bail may 45 be easily disengaged from the body by turning it over in such a direction as indicated by the arrow in Fig. 4 until the long side part 31 comes parallel to opening 21. The 50 bail then occupies such a position as shown in dotted lines at "A" in Fig. 2. Then the bail is slid longitudinally until the flat portions 24 are opposite opening 21, and then 55 by turning the bail down in the direction 60 shown by the arrow in Fig. 2, so that the

flats 24 are in proper position relative to opening 21, the bail may be easily slipped through the opening. This described method of procedure need not be followed exactly as to sequence; but it will be readily seen 70 that in order to remove the bail it is necessary to turn it to a position at an angle to its normal operative position and also to slide it longitudinally through the notch and also to turn it again about another axis of revolution and then to move it outwardly and downwardly, in order to release it from the body. Thus it is apparent that the bail is extremely unlikely to ever become accidentally disengaged from the body, even while 80 out of use or while being moved from place to place. In fact it is almost impossible for a bail so to become accidentally disengaged. There is only one particular position in which the bail will disengage from 85 the body. That particular position is very unlikely to be accidentally assumed by the bail; but at the same time it is very easy for a person purposely to put the bail in that position. Even while the elevator stands on a floor the bails cannot disengage. It will be noticed that, with the elevator standing on a surface S (see Fig. 2) the bail can only fall from position "A" to position "B". In position "B" the flats 24 are not in line with 90 opening 21; the plane of the flats, which in this case is also the plane of the bail, cannot be turned down far enough to line up with the diagonal downward-and-outward direction of the opening, due to the fact that the 100 opposite side 23^a of the bail rests on the floor before such position is reached.

Having described a preferred form of my invention, I claim:

1. In a device of the character described, 105 a removable supporting bail, and a body having a notch with a transverse inner part adapted normally to carry the bail extending transversely through it and having a diagonal outer opening adapted to pass the 110 bail only when it is in line with said outer opening.

2. In a device of the character described, 115 a continuous supporting link, a body having a notch with a transversely disposed inner part adapted to carry the link and a diagonally disposed contracted outer opening, and a reduced part in the link adapted to be passed through the notch opening when the reduced part is in line with the 120 notch opening, said reduced part being the only part of the link passable through the notch opening.

3. In a device of the character described, 125 a body having a notch with a restricted opening, a removable bail adapted normally to be carried in the notch, the bail being of larger size than the notch opening, and having a reduced portion at a point removed from the part of the bail that normally en- 130

- gages the notch; and the notch opening being positioned diagonally with reference to the inner part of the notch.
4. In a device of the character described, 5 a body having a notch with an inner portion and a restricted outer opening, said opening being positioned diagonally with reference to the inner part of the notch, and a bail adapted normally to be engaged in the 10 notch and having a reduced part, removed from the part normally engaging the notch, passable through the restricted opening.
5. In a device of the character described, a body having a bail receiving notch with 15 a relatively restricted opening; a supporting bail adapted to be carried in said notch, the part of the bail that normally engages the notch being curved, another part of the bail being substantially straight, and the 20 notch opening being also substantially straight to pass the corresponding part of the bail.
6. In a device of the character described, a body having a bail receiving notch with 25 a bail passing opening; a supporting bail adapted to be carried in said notch, the part of the bail that normally engages the notch being curved, another part of the bail being substantially straight, the inner part of the 30 notch being shaped to take the curved part of the bail, and the notch opening being also substantially straight to pass the corresponding part of the bail.
7. In a device of the character described, 35 a body with a notch having a bail passing opening, a supporting bail adapted to be carried in the notch, the bail in its normal operative position being substantially upright and having a curved lower end where 40 it normally engages the notch, said lower end being curved in a substantially vertical plane, the inner part of the notch that normally receives the bail being shaped to pass the curved part of the bail, and the 45 notch opening extending in a direction laterally from the inner part of the notch and the opening being substantially straight.
8. In a device of the character described, a body having a bail receiving notch the inner part of which extends substantially horizontally, the outer opening of said notch being restricted and positioned diagonally with reference to the extent of the notch, and the direction of the opening from the 55 inner part of the notch being diagonally downwardly and outwardly; a supporting bail normally in a substantially upright position and having a curved lower part normally engaging notch, said inner notch part being shaped to pass said curved bail part, said bail having a substantially straight portion in its vertical reach, and the notch opening being correspondingly substantially straight and of a width to pass the 60 corresponding part of the bail.
9. In a device of the character described, a body having a bail receiving notch the inner part of which extends substantially horizontally, the outer opening of said notch being restricted and positioned diagonally 70 with reference to the extent of the notch, and the direction of the opening from the inner part of the notch being diagonally downwardly and outwardly; a supporting bail normally in a substantially upright 75 position and having a curved lower part normally engaging the inner part of the notch, said inner notch part being shaped to pass said curved bail part, said bail having a substantially straight and reduced portion in its vertical reach, and the notch opening being correspondingly substantially straight and of a width to pass the correspondingly reduced part of the bail.
10. In a device of the character described, a body having a bail receiving notch with a restricted outer opening, said opening extending diagonally outwardly and downwardly from the inner part of the notch, a bail having a lower curved end part normally engaged in the inner part of the notch and having substantially straight upward reaches, one of said reaches being flattened to reduce its thickness sufficiently to pass through the restricted notch, and the plane 90 of said flattening being substantially the plane of the bail.
11. In a device of the character described, a body having a notch with a restricted outer opening, a removable bail adapted to be carried in the inner portion of the notch, and a reduced part in the bail passable through the restricted outer portion of the notch, said reduced part being the only part of the bail passable through the outer portion of 100 the notch.
12. In a device of the character described, a body having a notch with a restricted outer opening, a removable bail adapted to be carried in the inner portion of the notch, and a reduced part in the bail spaced from the part normally engaged in the notch and passable through the outer portion of the 110 notch.
13. In a device of the character described, a body having a notch with a restricted opening, a removable bail adapted to be carried in said notch, the part of the bail normally engaging the notch being not passable through the restricted opening, and the bail having another removed part which is passable through the restricted opening.
14. In a device of the character described, a body having a bail receiving notch with a restricted bail passing opening, a supporting bail carried in said opening, said bail being for the most part of larger size than can pass through said opening, but having a reduced part passable through said opening, and the reduced part being located on 125 130

the bail in such reference to the position of the notch opening that the reduced part will be out of register with said opening when the body and the bails are resting on a surface.

15. In a device of the character described, a body having a bail receiving notch with a restricted outer opening, a removable bail

carried in the notch, the bail having a part of reduced thickness passable through the notch only when the bail is out of normal operating position.

In witness that I claim the foregoing I have hereunto subscribed my name this 23rd day of March 1923.

CHARLES E. WILCOX.
